UNITED STATES PATENT OFFICE.

CHAUNCEY N. DUTTON, OF NEW YORK, N. Y.

TRUSS OR FRAME.

SPECIFICATION forming part of Letters Patent No. 321,469, dated March 21, 1893.

Application filed August 12, 1897. Serial No. 647,981. (No model.)

To all whom it may concern:

Be it known that I, CHAUNCEY N. DUTTON, of the city, county, and State of New York, have invented a certain new and useful Improvement in Trusses or Frames, of which improvement the following is a specification.

The object of my invention is to provide a truss or braced frame for use in buildings, bridges, docks, or other structures in which a load, either permanent or intermittent, is to be supported, in which truss all the web members shall be in compression and one chord only in tension.

To this end my invention, generally stated, consists in the combination of an inwardly curved or bent upper chord member, a lower chord member curved in the same direction, and connections uniting the chord members, and web members interposed between the chord members.

The improvement claimed is hereinafter fully set forth.

In the accompanying drawings, Figures 1 and 2 are side views illustrating trusses embodying my invention.

Referring first more particularly to the combination shown in Fig. 1, which is designed, primarily, for a timber construction for uniform or central load, in the practice of my invention I provide an upper chord member 1 and a lower chord member 2, each of which is preferably of timber. The upper chord member is inwardly or downwardly curved or bent on a segment of a circle of comparatively large radius or in a series of connected chords of arcs and the lower chord member is curved in the same direction, but on a shorter radius. The upper and lower chord members are connected adjacent to their ends in substantially the form of a crescent—in this instance by keys 3—and are held apart intermediately of their connections by interposed web members or struts 4. The truss rests at or near its ends on rigid supports or abutments 5. Under such construction the lower chord member only is in tension and the upper chord and web members are compression members.

When load is applied to the truss, its tendency is to curve the truss into a sharper crescent, the web members or struts holding the chord members a fixed distance apart, so

that their moments are a uniform ratio. The upper chord member is necessarily in a curved or broken line convex toward the lower chord member, since if it were concave toward the lower chord member the web members would be in tension and their joints with the chord members would necessarily be in tension, which is undesirable in a purely timber structure. If the upper chord members were straight, the strains would be uncertain and would depend upon the chance of the upper chord springing in one or the other direction. If it sprung toward the lower chord member, the strains would be compressed, while, as would probably be the case when the load was applied to the lower member, if it sprung away from the lower member the web members would be in tension, which possibility is precluded by the construction described and shown.

Fig. 2 illustrates the application of the essential features of my invention in an elastic beam adapted to use as a buffer or spring. To this end the web members are formed of springs 4^a, which may be either helical, as shown, or of any other preferred type, and the simple key connection shown in Fig. 1 should be replaced or supplemented by a stiff plate or plates 3^a at each end, to which the chord members are connected by bolts 6, and the ends should be confined so that the truss cannot spring backward. This is preferably effected by means of adjustable gibs 7, fitting on bed-plates 8 on the piers or supports 5, and the ends of the truss are provided with bearing-plates 9, abutting against the bed-plates and gibs, so that the truss can shorten and lengthen as its load is increased or decreased or when it is subjected to shock.

I claim as my invention and desire to secure by Letters Patent—

1. In a truss or frame, the combination of an outwardly-convex tension-chord, a compression-chord curved in the same direction, connections uniting the chord members, and compression web members interposed between the chord members.

2. In a truss or frame, the combination of an outwardly-convex tension-chord member, a compression-chord member curved in the same direction, end connections uniting the chord members, and spring compression web

members interposed between the chord members.

3. The combination of a truss or frame, composed of an outwardly-convex tension-chord member, a compression-chord member curved in the same direction, end connections uniting the chord members, interposed compression web members and fixed supports,

bed-plates secured thereto, and adjustable members interposed between the truss and said bed-plates.

CHAUNCEY N. DUTTON.
